TRAIN DISPATCHING SYSTEM FOR RAILROADS

Filed Nov. 22, 1928

UNITED STATES PATENT OFFICE

SEDWICK N. WIGHT, OF ROCHESTER, NEW YORK, ASSIGNOR TO GENERAL RAILWAY SIGNAL COMPANY, OF ROCHESTER, NEW YORK

TRAIN DISPATCHING SYSTEM FOR RAILROADS

Application filed November 22, 1928. Serial No. 321,185.

This invention relates to train dispatching systems of the synchronous selector type, and more particularly to a novel arrangement of relays for controlling a switch machine and the starting and entering signals at the end of a passing siding.

It is well understood, that it may be necessary to hold all of the signals at the end of a single track section at stop, or to clear any one of the signals at the end of a passing siding, in systems where the movement of trains is entirely dispatched by wayside signal indications. Also, in order to expedite the movement of trains it is desirable to operate the track switches at the ends of passing sidings from a distant point. In a synchronous selector train dispatching system, such as disclosed in the prior application of Neil D. Preston, Ser. No. 199,825 filed June 16, 1927, the circuits through which the distance control relays are operated are only momentarily completed, and for this reason it is desirable to employ control relays of the type which if momentarily energized assume a corresponding position, and remain in such position until energized with current of opposite polarity.

In accordance with the present invention it is proposed to use relays of this construction, and to momentarily energize such a relay with current of one polarity when it is to perform one particular function, and energize such relay momentarily with current of the reverse polarity when it is to perform another function. More specifically it is proposed to have one relay of the character mentioned for operating the switch machine, to employ another relay of the same character for determining the direction or movement of trains, and to employ a third relay of this character for determining whether a signal may indicate proceed in accordance with traffic conditions in advance thereof, or whether such signals shall remain at stop.

Other objects, purposes and characteristic features of the invention will be in part, obvious from the accompanying drawing and will in part be pointed out in the specification hereinafter.

One embodiment of the present invention

has been illustrated in the single figure of the drawing, in which the apparatus in the dispatcher's office has been conventionally shown and included within a dotted rectangle, and in which the way station apparatus at one end of the passing siding has been conventionally illustrated.

Referring to the drawing it will be noted that one end of the passing siding PS leading into a single track section O of a single track railway has been illustrated. That portion of the railway track comprising the detector track circuit including battery 3 and detector track relay DE, has been insulated from the rest of the track by insulating joints 4, the usual cross bonding of the rails having been omitted for convenience. The main and dwarf starting signals have been designated 2 and 2^d respectively. Similarly, the main entering signal has been designated 1 and the take-siding signal has been designated 1^d.

It is understood that these signals form part of the usual type of absolute-permissive-block signalling systems, in which the entering signals at opposite ends of a single track section are interlocked, all in a manner as disclosed in the prior application of S. N. Wight, Ser. No. 120,423 filed July 3, 1926; from which it appears that trains can be permitted to enter a single track section at one end only at a particular time. For convenience the absolute-permissive-block signalling wiring has been omitted, this having been conventionally represented by the home relays 1H and 2H, which home relays may be controlled as disclosed in said Wight application.

The track switch at the east end of the passing siding PS has been designated SE and is preferably operated by a switch machine SME conventionally shown by the dotted rectangle. This switch machine is operated to its normal position in the event that the normal wire N is energized and is operated to the reverse or take-siding position in the event the reverse wire R is energized, one or the other of these wires N or R being connected to the positive terminal of a suitable battery, or other source, depending

upon the position of the switch machine relay SMR at that time.

The signals 1, 1^d, 2, and 2^d are controlled in accordance with the position of the switch machine SME, the position of the direction relay DR and the position of the signal relay SR, and depending upon traffic conditions in advance of such signals as determined by the condition of energization of the home relays 1H and 2H. The wayside station equipment also includes a battery 9 for transmitting an OS indication to the dispatcher's office DO when the detector track circuit at said wayside station is occupied.

15 In the dispatcher's office is provided a miniature track layout, of which one end of the passing siding *ps* only has been illustrated. This miniature track layout in practice conforms in every detail to the actual track layout, indicating lamps corresponding to the various detector track circuits, or other track sections, being employed, of which the indicating lamp IE corresponding to the detector track circuit shown only has been illustrated.

20 25 Associated with the east end of the passing siding *ps* of the miniature track layout are a switch machine lever LSME and a direction signal lever LDE. The positions of these levers determine the position of the relay SMR and SR—DR, respectively, in a manner as more clearly pointed out hereinafter.

The synchronous selector system, whereby the distant control relays are controlled over a single line circuit, has, for convenience, been conventionally illustrated by the two selector or distributor arms, one of which is for convenience called a selector arm SA, and the other of which is for convenience called a distributor arm DA. This synchronous selector system may be one or any suitable type, for instance, such as shown in the Preston application above referred to, and in this system, the arms SA and DA are either rotated in synchronism continuously, are at rest part of the time and rotated at other times, or as disclosed in said Preston application the selector arm SA rotates at all times and the distributor arm DA operates only when required.

In order to get a more clear understanding 50 of the present invention it is deemed expedient to briefly consider the operation of the system.

Operation.—Let us assume that there is a train standing on the main track of a passing siding PS, and that the dispatcher wishes this train to proceed into the single track section O. In order to do so, he will move his lever LDE to the right-hand position, signifying east bound movement, and thereby momentarily close the following circuit for the direction relay DR:—beginning at the battery 10, wires 11, 12, and 13, lever contact LDE, wire 14, contact *s*¹; selector arm SA, message wire 15, distributor arm DA, distributor contact *d*¹; wire 16, winding of the direction

relay DR, wires 17, 18, and 19 to the common return wire C connected to the mid-point of battery 10. The momentary application of current of positive polarity to this relay does not change the position of its contact, because it has already assumed the corresponding position.

An instant later during the rotation of the arms SA and DA, namely, when these arms reach the stationary contacts *s*² and *d*², respectively, the following circuit for the signal relay SR is momentarily completed:—beginning at the battery 10, wires 11, 12, 20, and 21, lever contact 22 in its right-hand position, wire 23, contacts *s*² and SA, wire 15, contacts DA and *d*², wire 24, winding of the signal relay SR, wires 25, 26, 18, 19 and C, to the mid-point of battery 10. Momentary completion of these circuits causes the signal relay SR to move to its right-hand position, but does not change the position of the direction relay DR, because it already assumes its right-hand east bound position.

It may be pointed out here that these relays SMR, SR and DR are polar relays employing soft iron armatures and permanent magnets, together with coils for diverting the flux of the permanent magnet to operate the armature in one direction or the other, depending on the polarity of the current, where the armature will remain until changed by flow of current of opposite polarity, such for instance, as shown in the patent to Hubinger No. 786,901 granted April 11, 1905.

With these relays SR and DR in their right hand positions, the following circuit for the signal 2 is completed, assuming, of course, that traffic conditions in advance are favorable and that home relay 2H is energized:—beginning at the terminal B of a suitable source of current, contact 30 of the signal relay SR in its right hand position, wire 31, contact 32 of the relay DR in its right-hand position, wires 33 and 34, switch machine contact 35, wire 36, neutral contact 37 of the home relay 2H, polar contact 38 of this same home relay, wire 39, signal mechanism of signal 2, to the common return wire C connected to the other terminal of said source of current.

Clearing of the signal 2 informs the engineer of the train on the main track of passing siding PS that he may proceed into the single track section O. Passage of the train in question by the signal 2, effects de-energization of the detector track relay DE and causes the indicating relay IR in the dispatcher's office DO to be energized through the following circuit:—beginning at the battery 9, wire 40, contacts *d*⁴ and DA, message wire 15, contacts SA and *s*⁴, wire 41, winding of the indicating relay IR, wires 42, C, 19 and 43, back contact 44 of the detector track relay DE, wire 45 back to the battery 9.

It is noted that the circuit just traced

is momentarily completed successively once during each revolution of the arms SA and DA, and this indicating relay IR is constructed to be sufficiently slow-dropping so as not to assume its de-energized position during the intervening period so that this indicating relay IR is continuously energized so long as the detector track relay DE remains de-energized. With the indicating relay IR energized the indicating lamp IE is illuminated through the medium of a circuit readily traced in the drawing. If the train in question passes off of the detector track circuit the indicating lamp IE is again extinguished for obvious reasons.

Let us now assume that the dispatcher wishes to return the signal 2 to its stop position. In order to accomplish this, he will move his lever LDE back to its neutral position in which the following circuit for the signal relay SR is momentarily completed:—beginning at the negative terminal of the battery 10, wires 46, 47, and 48, lever contact 22 in its neutral position, wire 23, contacts s^2 and SA, message wire 15, contacts DA and d^2 , wire 24, winding of the signal relay SR, wires 25, 26, 18, 19 and C, back to the mid-point of battery 10. The closure of this circuit applies negative polarity to the signal relay SR, thereby returning its contact 30 to its left-hand position.

Let us now assume that the dispatcher wishes a west bound train in the single track section O to take the side track of the passing siding PS. In order to do so he must operate the switch machine and set up west bound traffic. The operator will first operate the switch machine lever LSME to its left hand position, thereby momentarily completing the following circuit:—negative terminal of the battery 10, wires 46, 47, and 50, lever contact LSME in its left hand position, wire 51, contacts s^3 and SA, message wire 15, contacts DA and d^3 , wire 52 winding of the switch machine relay SMR, wires 53, 26, 18, 19, and C, to the mid-point of battery 10. The completion of this circuit will cause the contact 54 of the switch machine relay SMR to assume its left-hand position, thereby energizing the reverse wire R and causing the switch machine SME to be operated to its take-siding position.

The dispatcher will then move his lever LDE to the left-hand position, thereby causing the signal relay SR to be moved to its right-hand dotted position, for reasons heretofore given. Also, with the lever LDE in the left hand position the following circuit for operating the direction relay DR to its dotted position is completed:—beginning at the negative terminal of the battery 10, wires 46, and 55, contact LDE in its left-hand position, wire 14, contacts s^1 and SA, message wire 15, contact DA and d^1 , wire 16, winding of the direction relay DR, wires 17, 18, and

19 and C, back to the mid-point of battery 10. The completion of this circuit causes the contact 32 of the direction relay DR to move to the left hand position, thereby completing the clearing circuit for the take-siding signal 1^d , which may be traced as follows:—beginning at the terminal B, contact 30 of the relay SR, wire 31, contact 32 of the relay DR in its left hand position, wires 57 and 58, switch machine contact 59 assuming its lower dotted position, wire 60, mechanism of the take siding 1^d to common return wire C connected to the other side of the battery. The engineer of the train is thus informed that he is to take the siding, and as he enters the same will cause the indicating lamp IE in the dispatcher's office to be illuminated, so long as he is occupying the detector track circuit.

Let us now assume that there is an east bound train standing on the side track of passing siding PS, and that the dispatcher wishes this train to proceed into the single track section O. Let us assume that the lever LSME is in the left hand position, indicating that the switch machine SME is assuming the take-siding position, and let us further assume that his lever LDE is in the right hand position, indicating east bound traffic. Under these conditions, for reasons already explained, the switch machine will assume the take-siding position and the relays SR and DR will both assume the right hand position, in which case the following circuit for the starting dwarf signal 2^d is completed:—beginning at the terminal B of a suitable source, contact 30, wire 31, contact 32, wire 33, switch machine contact 35 in the dotted position, wire 63, neutral contact 64 of the home relay 2H, polarity contact 65 of this same relay, wire 66, signal mechanism of the dwarf signal 2^d to common return wire C connected to the other terminal of said source. Also, with the switch machine assuming the main track position, the signal relay SR assuming the right hand position and the direction relay DR assuming the left hand position, the following circuit for the signal 1 is completed:—beginning at the terminal B of a suitable battery, contact 30, wire 31, contact 32 assuming the left hand position, wires 57 and 58, switch machine contact 59 in its solid line position, wire 67, neutral contact 68 of the home relay 1H, polar contact 69 of this same relay, wire 70, mechanism of the signal 1 to common return wire C connected to the other terminal of said battery. The completion of this circuit effects clearing of the signal 1.

It is thus noted that anyone of the 4 signals $1, 1^d, 2$, and 2^d may be cleared, or they may be all held at stop, and that the switch SME may be operated to either of its positions, all through the medium of two levers and three control channels, through the synchronous

selector system. Further, it is noted that occupancy of the detector track circuit is indicated over a separate channel.

Having now shown and described only a single specific embodiment of the present invention, it is desired to be understood that the specific circuit arrangement illustrated is not necessarily the exact circuit arrangement preferably employed in practicing the invention, but that the particular system illustrated has been selected to disclose an embodiment of the invention rather than its scope or the exact construction preferably employed in practicing the invention, and it is further desired to be understood that three aspect light signals may be used instead of the three position semaphore signals shown, if desired, and that various other changes and modifications may be made to adapt the invention to the particular dispatching problem to be solved by the invention, all without departing from the scope of the invention, or the idea of means underlying the same, except as demanded by the scope of the following claims.

What I claim is:—

1. In a train dispatching system of the synchronous selector type, the combination with two synchronously operated devices one at a train dispatcher's office and the other at a way station connected by a line wire and successively completing a plurality of control circuits, of a three-position lever in the dispatcher's office for applying current of one polarity to one of said control circuits when in its neutral position and applying current of the reverse polarity to said one circuit when in either extreme position, a polar permanent magnet stick type relay at said way station connected in said one control circuit, a contact on said lever for applying current of one polarity to another of said control circuits when said lever is in one extreme position and applying current of the reverse polarity to said another control circuit when in its other extreme position, another polar relay of the permanent magnet stick type at said way station connected in said another control circuit, two signals one governing the movement of traffic in one direction and the other governing traffic moving in the other direction, a circuit for clearing one of said signals closed only if said one relay is in its abnormal condition and the other relay is in its normal condition, and a circuit for clearing the other signal closed only when both of said relays assume the abnormal condition, whereby either of said signals may be cleared or both of said signals held at stop.

2. In a train dispatching system of the synchronous selector type; the combination with two synchronously operated contact arms one at a train dispatcher's office and the other at a way station connected by a line wire and successively completing a plurality of control circuits; of a lever for including a direct current source of either polarity in one of these circuits at the dispatcher's end; a relay of the polar permanent magnet stick type in said one circuit; said relay if momentarily energized by current of one polarity assuming a particular position until energized by current of the opposite polarity; another relay of the polar permanent magnet stick type controlled through the medium of another of said control circuits; two signals one govern-

ing the movement of trains in one direction and the other governing the movement of trains in the other direction; a circuit, which if closed causes one of said signals to indicate proceed, closed if one of said relays assumes the normal position and the other relay assumes the abnormal position; a second circuit for causing the other signal to indicate proceed closed when both of said relays assume the abnormal position.

3. In a train dispatching system of the synchronous selector type, the combination with two synchronously operated contact arms one at a train dispatcher's office and the other at a way station connected by a line wire and successively completing a plurality of control circuits, of a three-position lever in the dispatcher's office for applying current of one polarity to one of said control circuits when in its neutral position and applying current of the reverse polarity to said one circuit when in either extreme position, a polar permanent magnet stick type relay at said way station connected in said one control circuit, a contact on said lever for applying current of one polarity to another of said control circuits when said lever is in one extreme position and applying current of the reverse polarity to said another control circuit when in its other extreme position, another polar relay of the permanent magnet stick type at said way station connected in said another control circuit, two signals one governing the movement of traffic in one direction and the other governing traffic moving in the other direction, a circuit for clearing one of said signals closed only if said one relay is in its abnormal condition and the other relay is in its normal condition, and a circuit for clearing the other signal closed only when both of said relays assume the abnormal condition, whereby either of said signals may be cleared or both of said signals held at stop.

4. In a train dispatching system of the synchronous selector type, the combination with two synchronously operated contact arms one at a train dispatcher's office and the other at a way station connected by a line wire and successively completing a plurality of control circuits, of a three-position lever in the dispatcher's office for applying current of one polarity to one of said control circuits when in its neutral position and applying current of the reverse polarity to said one circuit when in either extreme position, a polar permanent magnet stick type relay at said way station connected in said one control circuit, a contact on said lever for applying current of one polarity to another of said control circuits when in one extreme position and applying current of the reverse polarity to said another control circuit when in its other extreme position, another polar relay of the permanent magnet stick type at said way station connected in said another control circuit, two signals one govern-

- control circuit, a track switch for diverting traffic either into a main track or into a siding; four signals one governing the movement of traffic off of the main track, a second signal governing the movement of traffic off of the siding, a third signal governing the movement of traffic onto the main track and a fourth signal governing the movement of trains onto the siding; a circuit for clearing said one signal closed only when said track switch is in the main track position and both of said relays are in their abnormal position; a circuit for said second signal closed only if said track switch assumes the take-siding position and both of said relays assume their abnormal position; a circuit for clearing said third signal closed only if said track switch assumes the main track position, said one relay assumes its abnormal position and said other relay assumes its normal position; a circuit for clearing said fourth signal closed only if said track switch assumes the take-siding position and both of said relays assume the abnormal position; whereby each signal may be cleared separately, and all signals assume the stop position if said lever assumes the neutral position.
5. In a train dispatching system of the synchronous selector type, the combination with two synchronously operated contact arms one at a train dispatcher's office and the other at a way station connected by a line wire and successively completing a plurality of control circuits, of a three-position lever in the dispatcher's office for applying current of one polarity to one of said control circuits when in its neutral position and applying current of the reverse polarity to said one circuit when in either extreme position, a polar permanent magnet stick type relay at said way station connected in said one control circuit, a contact on said lever for applying current of one polarity to another of said control circuits when in one extreme position and applying current of the reverse polarity to said another control circuit when in its other extreme position, another polar relay of the permanent magnet stick type at said way station connected in said another control circuit, a track switch for diverting traffic either into a main track or into a siding; four signals one governing the movement of traffic off of the main track, a second signal governing the movement of traffic off of the siding, a third signal governing the movement of traffic onto the main track and a fourth signal governing the movement of traffic onto the siding; a circuit for clearing said one signal closed only when said track switch is in the main track position and both of said relays are in their abnormal position; a circuit for said second signal closed only if said track switch assumes the take-siding position and both of said relays assume their abnormal position; a circuit for clearing said third signal closed only if said track switch assumes the main track position, said one relay assumes its abnormal position and said other relay assumes its normal position; a circuit for clearing said fourth signal closed only if said track switch assumes the take-siding position and both of said relays assume the abnormal position; a detector track circuit including a track relay associated with said track switch; and a back contact of said track relay included in series with an indicating means at the dispatcher's office included in a third of said control circuits.
6. Control means for controlling a starting signal governing the entrance of traffic into a single track section and controlling a leaving signal governing the movement of traffic out of such single track section comprising, a double throw contactor cooperating with two stationary contacts connected respectively with said starting signal and with said leaving signal, a second contactor for applying energy to said double throw contactor, a selector system operatively connecting said contactors with a remote point for controlling said contactors to one or the other of their positions sequentially in the same operating cycle.
7. Control means for controlling a starting signal governing the entrance of traffic into a single track section and controlling a leaving signal governing the movement of traffic out of such single track section comprising, a double throw contactor cooperating with two stationary contacts connected respectively with said starting signal and with said leaving signal, a second contactor for applying energy to said double throw contactor, and a selector system operatively connecting said contactors to a remote point for controlling said contactors from such remote point to positions depending upon the polarity of current transmitted over said selector system.
8. In combination, a track switch connecting the end of a passing siding to a single track section, two starting signals and two entering signals governing respectively the movement of traffic into and out of said single track section, a starting signal branch circuit, an entering signal branch circuit, a double throw contactor controlled in accordance with the position of said track switch for connecting said starting signal branch circuit to one or the other of said starting signals, a second double throw contactor controlled in accordance with the position of said track switch for connecting said entering signal branch circuit to one or the other of said entering signals, a third double throw contactor for applying electrical energy to one or the other of said two branch circuits, a fourth contactor for cutting energy off of said third contactor, and a selector system op-

eratively connecting said contactors with a remote point for controlling said contactors to one or the other of their positions sequentially in the same operating cycle.

9. In combination, a track switch connecting the end of a passing siding to a single track section, two starting signals and two entering signals governing respectively the movement of traffic into and out of said single track section, a starting signal branch circuit, an entering signal branch circuit, a double throw contactor controlled in accordance with the position of said track switch for connecting said starting signal branch circuit to one or the other of said starting signals, a second double throw contactor controlled in accordance with the position of said track switch for connecting said entering signal branch circuit to one or the other of said entering signals, a third double throw contactor for applying electrical energy to one or the other of said two branch circuits, and a fourth contactor for cutting off said electrical energy, a fifth contactor for controlling said track switch to either of its two extreme positions; and a selector system for controlling said third, said fourth and said fifth contactor to one or the other of their positions depending upon the polarity of currents transmitted over said selector system.

10. In combination, a track switch connecting the end of a passing siding to a single track section, two starting signals and two entering signals governing respectively the movement of traffic into and out of said single track section, a starting signal branch circuit, an entering signal branch circuit, a double throw contactor controlled in accordance with the position of said track switch for connecting said starting signal branch circuit to one or the other of said starting signals, a second double throw contactor controlled in accordance with the position of said track switch for connecting said entering signal branch circuit to one or the other of said entering signals, a third double throw contactor for applying electrical energy to one or the other of said two branch circuits, and a fourth contactor for cutting off said electrical energy, a fifth contactor for controlling said track switch to either of its two extreme positions; and a selector system for controlling said third, said fourth and said fifth contactor to one or the other of their positions sequentially in the same operating cycle.

11. In combination, a track switch connecting the end of a passing siding to a single track section, two starting signals and two entering signals governing respectively the movement of traffic into and out of said single track section, a starting signal branch circuit, an entering signal branch circuit, a double throw contactor controlled in accordance with the position of said track

switch for connecting said starting signal branch circuit to one or the other of said starting signals, a second double throw contactor controlled in accordance with the position of said track switch for connecting said entering signals, a third double throw contactor for applying electrical energy to one or the other of said two branch circuits, and a fourth contactor for cutting off said electrical energy, a fifth contactor for controlling said track switch to either of its two extreme positions; and a selector system for controlling said third, said fourth and said fifth contactor to one or the other of their positions depending upon the polarity of currents transmitted over said selector system.

12. Control means for controlling a starting signal governing the entrance of traffic into a single track section and controlling a leaving signal governing the movement of traffic out of such single track section comprising, a double throw contactor cooperating with two stationary contacts connected respectively with said starting signal and with said leaving signal, a second contactor for applying energy to said double throw contactor, means for independently controlling said contactors in accordance with the polarity of current transmitted from a remote point, and means for controlling the particular signal selected in accordance with traffic conditions ahead of such selected signal.

13. Control means for controlling a starting signal governing the entrance of traffic into a single track section and controlling a leaving signal governing the movement of traffic out of such single track section comprising, a double throw contactor cooperating with two stationary contacts connected respectively with said starting signal and with said leaving signal, a second contactor for applying energy to said double throw contactor, selector means for controlling said contactors to different positions independently and at different time periods in an operating cycle over the same circuit, and means for further controlling the particular signal selected in accordance with traffic conditions ahead of such signal.

14. In combination, a track switch connecting the end of a passing siding to a single track section, two starting signals and two entering signals governing respectively the movement of traffic into and out of said single track section, a starting signal branch circuit, an entering signal branch circuit, contactors controlled in accordance with the position of said track switch for connecting said starting signal branch circuit to one or the other of said starting signals, other contactors controlled in accordance with the position of said track switch for connecting said entering signal branch circuit to one or the other of said entering signals, a third set of contactors for applying electrical energy to one

or the other of said two branch circuits; and
a selector system for controlling said third
set of contactors to select one or the other of
said two branch circuits, said third set of con-
tactors being controlled in accordance with
5 the polarity of current transmitted over said
selector system.

In testimony whereof I affix my signature.
